UNITED STATES PATENT OFFICE.

GUSTAF A. ERICKSON, OF MINNEAPOLIS, MINNESOTA, ASSIGNOR TO
JOHN E. ERICKSON, OF ST. PAUL, MINNESOTA.

ARTIFICIAL LEG.

No. 832,851.

Specification of Letters Patent.

Patented Oct. 9, 1906.

Application filed April 12, 1906. Serial No. 311,292.

To all whom it may concern:

Be it known that I, GUSTAF A. ERICKSON, a citizen of the United States, residing at Minneapolis, in the county of Hennepin and State of Minnesota, have invented certain new and useful Improvements in Artificial Legs; and I do hereby declare the following to be a full, clear, and exact description of the invention, such as will enable others skilled in the art to which it appertains to make and use the same.

My invention relates to artificial legs, and has for its object to improve the same in the several particulars hereinafter noted.

The invention consists of the novel devices and combinations of devices hereinafter described, and defined in the claims.

In the accompanying drawings, which illustrate the invention, like characters indicate like parts throughout the several views.

Referring to the drawings, Figure 1 is a view in side elevation, showing an artificial leg embodying my invention. Fig. 2 is an enlarged vertical section taken on the line $x^2 x^2$ of Fig. 1, some parts being shown in full and some parts being broken away. Fig. 3 is a plan view of the socket-supporting ring removed from working position. Fig. 4 is a side elevation with some parts broken away, illustrating a slightly-modified form of the improved device. Fig. 5 is a vertical section taken through the parts shown in Fig. 4 at an angle of ninety degrees to the direction in which the said parts are shown in said Fig. 4, and Fig. 6 is a plan view of the supporting-ring shown in Figs. 4 and 5.

Referring first to the construction illustrated in Figs. 1, 2, and 3, the numeral 1 indicates the lower leg-section of an artificial leg, the same having the usual or any suitable foot 2. 3 indicates the thigh-socket, which is of the usual or any suitable construction and is connected to the leg-section 1 by a pair of hinged metallic thigh-straps 4 5, the upper sections 4 of which are rigidly connected to said thigh-socket, the lower sections of which at their lower ends are rigidly connected to the leg-section 1, and which strap-sections are pivotally connected at 6 to afford the usual knee joint or hinge. 7 indicates the so-called "slip-socket," which at its sides is provided with guide-channels that embrace

the edges of the lower sections of the thigh-straps and is guided for vertical movements thereby. The leg-section 1 at its upper end is provided with a metallic band 8, that telescopically embraces the lower end of the socket 7. The lower end of the socket is, as shown, reduced at 7^a, so that it telescopes within the cavity of the leg-section 1 and leaves a shoulder 7^b, surrounding the upper portion of said reduced portion 7^a. The shoulder 7^b of the slip-socket is supported upon a yieldingly - maintained supporting-ring 9. This supporting-ring 9 is connected to the upper portions of the lower sections 5 of the thigh-straps, preferably by coiled springs 10, the upper ends of which are, as shown, attached to headed studs 11 on said thigh-strap sections 5, and the lower ends of which springs are attached to upturned lugs or ears 9^a on the sides of said supporting-ring 9. To afford clearance for the springs 10, the thigh-strap sections 5 are preferably cut away or formed with vertical slots 5^a. In lieu of the springs 10 strong elastic straps may be employed; but the coiled springs are preferred. Normally, or when there is no weight on the slip-socket 7, the springs will hold the same upward, as shown in Fig. 2. When weight is put upon this slip-socket, it moves downward, and its downward movement is limited by the engagement of the supporting-ring 9 with annular or segmental cushion-strips 12, preferably of rubber, that are secured to the annular upper edge of the leg-section 1. The supporting-ring 9 and its ears or lugs 9^a move downward within the metallic band 8, so that the latter serves as a guard to prevent the said movable parts from coming in contact with the underwear or pantaloons-legs of the wearer of the artificial leg. When it is desired to remove the slip-socket from working position, it is simply raised or slid vertically upward on the lower sections of the thigh-straps, leaving the supporting-ring 9 suspended in normal position and ready to receive the slip-socket when it is again placed in working position. The said supporting-ring 9 may of course take any form desired in cross-section.

In the construction illustrated in Figs. 4, 5, and 6 the supporting-ring 12 is round in cross-section and is provided at diametrically

opposite points with radially-projecting studs 13, having notches 14 on the under sides of their end portions. In lieu of the springs 10 strong elastic webs 15 are used, and these are rigidly attached at their upper ends to the upper portions of the lower sections 5 of the thigh-straps, as shown, by means of screws 16 and clamping-plates 17. The lower ends of the webs 15 are preferably reinforced by thin metallic plates 18, that are perforated to receive the notched ends of the studs 13 of the supporting-ring 12. In this construction the lower sections of the thigh-straps may be narrower than in the construction previously described, as it is only necessary to provide therein small vertical slots 19, in which the studs 13 of the supporting-ring 12 may work to permit the free vertical movements of the slip-socket. 7.

With the construction just described the webs may be very easily detached at their lower ends from the studs of the supporting-ring.

In both forms of the device the slip-socket 7 may be easily lifted from working position. This is very desirable, because it is very convenient to apply the slip-socket to the leg-stump before putting on the artificial leg. It affords a complete and unbroken support for the slip-socket.

The device described is very simple, of small cost, and in practice has been found extremely efficient for the purposes had in view.

I claim as my invention—

1. In an artificial leg, the combination with a lower leg-section, a thigh-socket and hinged thigh-straps connecting the two, of a slip-socket movable therewith on the lower sections of said thigh-straps, a supporting-ring upon which said slip-socket loosely rests, and yielding devices supporting said supporting-ring from said lower leg-section, the connections between said ring and said yielding devices being made through slots formed in the lower thigh-strap sections, substantially as 45 described.

2. In an artificial leg, the combination with a lower leg-section, a thigh-socket and hinged thigh-straps connecting the two, of a slip-socket movable vertically on the lower sections of said thigh-straps, a supporting-ring upon which said slip-socket loosely rests, said supporting-ring having projections that work through vertical slots in the lower thigh-strap sections, and yielding connections attached at 50 their upper ends to the upper portions of the lower thigh-strap sections, and attached at their lower ends to the projections of said supporting-ring, substantially as described.

In testimony whereof I affix my signature 60 in presence of two witnesses.

GUSTAF A. ERICKSON.
